GAME APPARATUS

Archie J. McMaster, Highland Park, Ill., assignor
to G-M Laboratories, Inc., Chicago, Ill., a cor-
poration of Illinois

Application February 17, 1936, Serial No. 64,235

6 Claims. (Cl. 194—98)

The present invention relates generally to games for the amusement of the players and to apparatus therefor. It relates, also, to coin controlled amusement and vending apparatus.

5 The present invention concerns a new, novel and entertaining game to be played with coins, checks or tokens having distinguishing numbers, dates, legends or symbols thereon and with apparatus for selecting at random some particular 10 identifying character; the object of the game being to deliberately select a coin, check or token having the same identifying character as is selected at random by the machine whereby to match the coin, check or token with the selection 15 of the machine.

It is an object of the present invention to provide a new and improved game and apparatus for playing the same.

A further object consists in providing improved 20 means by which a player for the purpose of playing the game conveniently, easily, deliberately and overtly may indicate his guess or prediction as to what selection will be made by the random operation of the machine.

25 A further object is the provision of an improved coin controlled game apparatus and of an improved vending and amusement device.

A further object is the provision of improved 30 game apparatus for receiving a coin, check or token and displaying its identifying character to the view of the player, and for making a random selection of one identifying character from a number thereof and displaying the same for comparison with that of the coin, check or token.

35 A further object is the provision of means for illuminating the machine while the same is in use to aid and improve the view thereof by the player.

A further object is the provision of means con- 40 trolled by the player himself for illuminating the displays and for removing the coin, check or token from view after its inspection by the player and comparison with the random selection made by the machine itself to determine whether or 45 not the "matching" of the two has been accomplished.

These and other objects and advantages of my present invention will appear as the description proceeds.

50 My present invention in one embodiment thereof, comprises a wheel adapted to be spun and then to be stopped at random in one of a number of pre-determined rotated positions. In each of the positions in which the wheel may 55 stop, it exposes to view and indicates to the play-

er a character which includes the number of some year such as for example the number 1936. The player's prediction of the random selection to be made by the wheel is indicated by the date on the coin which he has inserted into the machine.

It, also, includes mechanism for spinning said wheel and for bringing it to a registered stop. It further includes coin controlled mechanism which permits the wheel to be spun only when 10 a coin has been inserted in the machine. Confections or the like, also, are dispensed under control of the coin mechanism.

The apparatus of my present invention includes, also, improved means for exposing the 15 identifying character of the check, token or coin to the view of the player, such as, for example, a magnifying glass for enlarging the appearance of the check or token and a battery operated electric light for illuminating the same, said light 20 being controlled by a switch operated as an incident of the player's operation of the apparatus.

The apparatus of my present invention fur- 25 ther provides means for placing the token, check or coin in close proximity to the indicator or display element of the apparatus itself so as to permit comparison of the two to be made at a glance.

Preferably the power required for operating 30 this mechanism of my improved apparatus is furnished mechanically by the player himself by actuating a lever or the like, although self contained mechanical or electrical actuators controlled by the player, also, are contemplated.

In order to conserve the life of the batteries 35 which operate the light already mentioned, the switch controlling the light preferably is ar- ranged to disconnect the lamp whenever the actuating or control lever occupies its normal position, that is the position which it assumes when released by the player, and to connect the lamp 40 to the battery whenever the lever is moved out of this rest position. Furthermore, according to one aspect of my present invention, the light is turned on by considerably less motion of the operating handle or lever than is required for 45 actuating the spinning indicating and selecting wheel or for performing any other function which may be required of the lever.

This permits the player at all times to illuminate the token or check in the apparatus and, 50 also, the random indicator of the apparatus, itself, while permitting the light to be left off when not required and when the apparatus is not in use so as to conserve and preserve the bat- 55 tery.

My invention further contemplates the provision of means operated by the lever which serves to advance the checks or tokens which are inserted into the machine from one position 5 to another within the machine itself and to advance the checks or tokens into and out of the view of the player. My present invention further contemplates that the movement of the checks or tokens within the machine and the 10 operation of the random indicating wheel all shall be accomplished by the same motion of the operating lever in such manner that the player cannot after making a play actuate one without actuating the other, also.

15 In order better to acquaint those skilled in the art with the teachings and practice of my present invention, I now shall describe a specific embodiment thereof, reference being had to the accompanying drawings forming a part of this 20 specification and in which:

Fig. 1 is a general view in perspective of the exterior of a coin controlled amusement and vending machine embodying my present invention.

25 Fig. 2 is a general view in perspective of a part of the interior mechanism of the device of Fig. 1.

Fig. 3 is another general view in perspective but from a different angle of the same apparatus as is shown in Fig. 2.

30 Fig. 4 is a diagrammatic representation of an electric circuit.

Fig. 5 is a sectional elevation of the device of Fig. 1 looking toward the left in Fig. 1 so as to provide a general view of a portion of the interior 35 of the device of Fig. 1.

Fig. 6 is a sectional elevation of the apparatus of Fig. 1 looking toward the right in Fig. 1 and showing in section the apparatus for delivering to the purchaser the article vended by the 40 machine.

Fig. 7 is a section taken along the line 7—7 of Fig. 6 in the direction indicated by the arrows so as to view the apparatus from above.

Fig. 8 is a section through the coin apparatus 45 in which the parts are shown in their normal position. It is a section taken along the line 8—8 of Fig. 10.

Fig. 9 is a sectional view similar to Fig. 8 but showing the parts in a different operated position. It is a section taken along the line 9—9 of Fig. 11.

Fig. 10 is a section taken along the line 10—10 of Fig. 8, showing the parts in the same positions as they occupy in Fig. 8.

55 Fig. 11 is a section taken along the line 11—11 of Fig. 9, showing the parts in the same positions as they occupy in Fig. 9.

Fig. 12 is a section taken along the line 12—12 of Fig. 8.

60 Fig. 13 is an elevational view of a portion of the mechanism shown in perspective in Figs. 2 and 3.

Fig. 14 is a section taken along the line 14—14 of Fig. 13.

65 The apparatus illustrated in Fig. 1 comprises a decorative metal enclosing case comprising a pair of end panels 11 and 12 and a formed metal sleeve 13. Mounted on top of the enclosing case and secured to the sleeve 13 thereof is a casting 70 14 having a hollow therein adapted to receive a check, token, coin or the like. At the bottom of the hollow of the casting 14 is a slot 15 in the sleeve 13 through which the coin or check may fall into the interior of the enclosing case. Journaled in the end plate 12 is a handle or lever 16

adapted to be depressed by the player or purchaser after the insertion of his check, token or coin to operate the machine. Operation of the machine by means of the handle 18 causes the coin to appear in view behind a lens 17. The 5 same operation of the machine, also, causes the machine to make a random selection which is indicated at an opening 19 through which the player may view or read the indication which the machine gives to reveal its own random selection. 10 The purchaser obtains his confection or other vended article by pressing a plunger 19 which causes the purchased article to be delivered into a pocket 20 at the front of the inclosing case from which he may take it. 15

The space immediately surrounding the opening 19 in the sleeve 13 is inclosed by a decorative frame 21 which is adapted to receive a name plate or a card of instructions or other descriptive matter. A key-lock, the key-hole of which is shown at 23, is provided for locking the machine in its assembled condition.

By unlocking the key-lock the mechanism shown in Figs. 2 and 3, including the end plate 12, may be separated from the rest of the apparatus by withdrawing it from the sleeve 13. The unit assembly shown in Figs. 2 and 3 includes the entire mechanism except the vending apparatus which remains with the end plate 11 and sleeve 13. The key-lock is shown at 25 in Fig. 3. The element with which the lock 25 engages is attached to the sleeve 13 and is not shown.

As best may be seen in Figs. 3 and 5, the lever 18 of Fig. 1 is secured to a shaft 27 which in turn carries a lever 28 which actuates a wheel 30 through a spring snap mechanism and an overrunning clutch mechanism. The snap mechanism and the details of its construction and operation are more completely described in the co-pending application of Karl H. Sommermeyer, Ser. No. 62,165, filed Feb. 3, 1936. The overrunning clutch mechanism and the wheel 30 are carried on a fixed shaft 31 and the driving member 51 of the over-running clutch mechanism includes an arm 32 which turns about the shaft 31. The lever 28 in the position in which it is shown in Fig. 5, stops against the hub of the arm 32 and in another position it stops against the bottom of the inclosing case. The arm 32 carries a pin 40 having a head 41 which is adapted to engage a pair of bosses 35 and 36 shown in section in Fig. 5 which project from the end plate 12 as shown in Fig. 3 and act as stops for the arm 32. The arm 28 has pivoted thereto at a pin 37, a cross piece or spreader 38. A spreader 39, also, is pivoted to the arm 32 by means of the pin 40; and a pair of springs 43 and 44 are tensioned between these spreaders. The levers 28 and 32 together with the springs 43 and 44 and 60 their spreaders 38 and 39 constitute the snap mechanism. The use of the two springs 43 and 44 with the two spreaders 38 and 39 serves to permit the line of action of the springs, which passes through pins 37 and 40, to cross the axis 65 of shaft 31 without requiring the shaft to be severed to permit a spring to pass therethrough. The spreader 39, also, constitutes a part of a latch mechanism for preventing operation of the wheel 30 when no coin has been inserted in the 70 machine; and for that purpose it is provided with a notch 45 near its upper end which engages a latch piece 46. The operation of this latch will be explained presently.

The snap mechanism operates as follows: The 75

springs 43 and 44 normally hold the levers 32 and 28 in the positions in which they are shown in Fig. 5. When the lever 18 (see Figs. 1 and 2) is depressed, it rotates the shaft 27 in a counter-clock-wise direction as viewed in Fig. 5 causing the lever 28 to move down through an arc such as to increase the distance between the pins 37 and 40 so as to increase the tension of the springs 43 and 44. As the pin 37 moves down, the line of action of the springs, that is, the line between the pins 37 and 40, crosses the axis of the shaft 31 so that the springs tend to rotate the lever or arm 32 in a clock-wise direction about the shaft 31. The arm 32 thereupon rotates with a snap 15 action until it stops against the boss 35. Because of the particular location of the boss 35 with respect to the levers 28 and 32, the line of action of the springs never crosses the axis of the shaft 27. Therefore, the springs continue 20 to urge the lever 28 toward the position shown in Fig. 5. When the lever 28 is permitted to return to that position, the line between the pins 37 and 40 again crosses the axis of the shaft 31 causing the arm 32 to snap back to the position 25 shown in Fig. 5 where it stops against the boss 35. The foregoing description of the operation of the snap mechanism assumes that the coin controlled latch including the latch piece 46 previously referred to, was disengaged. If no coin were inserted in the machine, the spreader 39 would be caught by the latch piece 46 so as to prevent the arm 32 from moving out of the position shown in Fig. 5.

The construction of the over-running clutch 35 mechanism and its driving connection with the wheel 30, as well as the mechanism for bringing the wheel to a registered random stop, is more completely described in the co-pending application of Walter Van Guilder, Ser. No. 62,164, filed 40 Feb. 3, 1936.

Referring now to Figs. 5, 13 and 14, the over-running clutch mechanism includes the housing 51 which constitutes the driving member of the clutch and which includes the arm 32 already 45 referred to. A driven member of the clutch 52 comprises a plate portion 53 and a bushing portion 54. The plate portion 53 is adapted to make driving engagement with the driving member 51 by means of a pair of steel balls 55 when the arm 50 32 rotates in a clock-wise direction as viewed in Fig. 5. When the arm 32 rotates in a counter-clock-wise direction as viewed in Fig. 5 the balls 55 act to release the driving engagement. The wheel 30 is mounted on a hub 59 which turns 55 freely on the bushing portion 54 of the driven member 52 of the clutch.

Pivottally secured to the web of the wheel 30 are a pair of weights 60 and 61 which are linked together by means of a tie bar 62 so that they 60 move together and are always symmetrically disposed with respect to the center of the wheel 30. The weights 60 and 61 are provided with spring toggles 65 and 66 which serve continually to urge 65 these weights in a direction which brings their centers of gravity near the center of the wheel 30. These spring toggles 65 and 66 are so arranged that when the centers of gravity of the weights 60 and 61 are at their maximum distances from the center of the wheel 30 (in which 70 position the weights bear against the inner surface of the rim of the wheel 30), the toggles 65 and 66 exert a comparatively small effort on the weights 60 and 61 so that a comparatively slight centrifugal force will be sufficient to hold them 75 in that position against the force of the spring

toggles. The weight 60 carries a dog 67 which is adapted to engage teeth 68 on the periphery of a wheel 69 secured to the shaft 31 in such a manner as to prevent rotation thereon.

The dog 67 normally is held in engagement 5 with the wheel 69 by the spring toggles 65 and 66.

The wheel 30 carries on its periphery a series of numbers or characters which constitute the numbers of years. Each one of the characters corresponds to one of the notches 68 of the 10 notched member 69, and each of the notches 68, when the dog 67 is seated therein brings one of the characters squarely into register in the center of the opening 73 in the panel 72 (see Fig. 2) where it may be viewed through the opening 15 or window 19 in the sleeve 13 of the enclosing case (see Fig. 1).

The driven member 52 of the over-running clutch mechanism carries a pin 70 which extends through a clearance hole in the web of the wheel 20 30 to engage a hole in the center of the tie bar 62. This pin 70 is the only driving connection between the member 52 of the over-running clutch and the wheel 30.

When the arm 32 of the over-running clutch 25 snaps in a clock-wise direction as viewed in Fig. 5 in the manner already described, it drives the member 52 of the clutch with it, which in turn through the pin 70 drives against the tie bar 62 tending to rotate it about the shaft 31 in a 30 counterclock-wise direction as viewed in Fig. 13. The driving force exerted on the tie bar 62 is resisted by the inertia of the wheel 30 so that the initial driving action disengages the dog 67 from the notched member 69 and moves the weights 35 60 and 61 out against the rim of the wheel 30. The wheel 30 is accelerated from the very beginning of the motion of the arm 32 and continues to accelerate until the arm 32 stops against the boss 35 (see Fig. 5). As soon as the arm 32 40 and the driving member 51 of the clutch stop, the balls 55 thereof release the member 52 so that the member 52 together with the wheel 30 continue to rotate. The rotation is retarded only by friction and after a time, the wheel decelerates 45 to such a speed that centrifugal force no longer holds the weights 60 and 61 out against the rim of the wheel 30. Thereupon the spring toggles 65 and 66 bring the dog 67 sharply into engagement with the teeth 68 of the member 69 so that 50 the dog 67 clicks over the notches and quickly brings the wheel to a stop. The dog 67 seats itself into one of the notches 68 so as to bring the wheel 30 to a stop accurately registered in a position corresponding to one of the notches 68. 55 This brings one of the numbers which constitute the design on the periphery of the wheel 30 into register in the center of an opening 73 (shown in Fig. 2) in the panel 72.

The mechanism just described cooperates with 60 certain coin controlled mechanism which receives and handles the coins and controls the latch piece 46. This latter mechanism is more fully described in the copending application of Walter Van Guilder and Karl H. Sommermeyer Ser. No. 65 67,842, filed March 9, 1936.

The panel 72 has secured thereto near the top thereof a metal channel piece 75 which co-operates therewith to form a groove or channel for a pair of coin detecting slides 77 and 78 (see Figs. 70 8, 9, 10, 11 and 12). Of these, slide 77 has a pin 79 extending through a slot in the channel 75 for engagement with slotted arm 80 which drives it (see, also, Fig. 3).

Referring to Fig. 3, a lever 92 secured to the 75

shaft 27 rotates therewith. A link 93 connects this lever 92 with another lever 94 which is carried on a pivot having the same axis as the lever 80. The link 93 has a slotted connection with the lever 94 so as to permit a certain amount of motion of the hand lever 18 and the shaft 27 to take place before the coin mechanism begins to operate. A projection 95 of the lever 94 engages the lever 80 to drive the same.

10 The arrangement of the cam 95 with respect to the lever 80 is such that the cam 95 drives the lever 80 only in one direction. That is, when the lever 18 (Fig. 1) is depressed, the lever 80 and the slide 77 are driven toward the left as viewed 15 in Fig. 3, and towards the right as viewed in Figs. 8, 9 and 12. A spring 81 attached to the lever 80 provides the effort for the return motion of the slide 77. This spring, also, normally retains the slide 77 in the position in which it is shown 20 in Figs. 8 and 12. The slide 77 lies behind an opening 38 in the panel 72 (see Figs. 3 and 12) adapted to receive coins from the opening 15 in the sleeve 13 of the enclosing case (see Fig. 1).

The slide 77, also, carries a projection 83 on 25 its forward face. This projection 83, the coin receiving space and the slide 78 are in alignment. The projection 83 is adapted to move towards the right as viewed in Figs. 8, 9 and 12 to crowd the coin against the end of the slide 78 and thereby to drive the slide 78 towards the right as viewed in Figs. 8, 9 and 12. The end of the slide 78 which faces the projection 83 is cut off at an angle and thereby is adapted to engage a coin 30 between it and the projection 83 so as to urge the coin downward into a coin trap 91, the opening into which is offset toward the right in Figs. 8 and 9 from the opening 86.

The slide 78 normally obstructs the opening 40 from the channel carrying the slides 77 and 78 into the coin trap 91 so that a coin must drive the slide 78 to the right (as seen in Figs. 8, 9 and 12) in order to pass into the coin trap 91. The spacing between the projection 83 of the slide 77 and the left end of the slide 78 as viewed 45 in Fig. 8 is so large and the limits of travel of the two slides is such that projection 83 never can engage slide 78. Consequently, slide 78 cannot be driven to the right as viewed in Fig. 8 unless a coin is in place as shown in Fig. 8, but 50 will be so driven when a coin is in place.

The extreme right end of the slide 78 as viewed in Fig. 12, is offset as shown at 84 in Fig. 12 to receive a spring 85 and for carrying the latch piece 43. Latch piece 46 already has been mentioned in connection with the driving mechanism for the wheel 30 and its operation will be described presently. The spring 85 normally holds the slide 78 in the position in which it is shown in Figs. 8 and 12, in which position the off-set portion 84 stops against the end of the channel piece 75 as may be seen in Fig. 12.

A shaft 110 carries a curved arm 111 which preferably is formed integrally therewith. A spring 113 holds the arm 111 in firm engagement 65 with a roller 112 carried by the pin 40 of the arm 32. The curvature of the arm 111 is such that the shaft 110 executes a counterclock-wise rotation (Fig. 5) when the arm 32 snaps down to spin the wheel 30. This shaft 110 operates a pin 90 which works in the coin trap 91, a catch 120 for the lever 80, and a lever 145 for controlling the confection dispensing mechanism.

Depending from the coin trap 91 is a hinged chute 101 which is adapted to guide a coin into 70 position behind an opening 102 in the panel 72

where it is supported upon projections 103 and 104 and where it may be viewed by the player. This chute 101 carries a pair of arms 105 and 106 which are adapted to be engaged by the arm 89 carrying the pin 90 and by the cam 95 of the lever 94 respectively for closing the chute 101 by holding it against the panel 72 so as to retain the coin in view in the opening 102. When the apparatus is in its normal position as shown in Figs. 3 and 10, the cam 95 of the lever 94 engages 10 arm 106 to hold the chute 101 closed. A spring 107 tends to hold the chute 101 away from the panel 72 so as to permit the coin to escape therefrom.

The pin 90 which is carried by the shaft 110 15 and the arm 89, normally extends into the coin trap 91 to obstruct the passage of coins therethrough; and it is adapted to be withdrawn from the coin trap to permit free passage of coins when the arm 32 of the snap mechanism snaps 20 down to spin the wheel 30. When the arm 89 withdraws the pin 90 from the coin trap 91, it engages the arm 105 to close the chute 101.

The catch 120 is adapted to block the return motion of the arm 80 and the slide 77 when the 25 arm 32 is in its down position and resting against the boss 36.

The latch already referred to, which restrains the motion of the snap mechanism which drives the wheel 30 consists of the latch piece 46 carried by the slide 77 of the spreader 39. As may be seen in Fig. 5, the points of fastening of the springs 43 and 44 to the spreader 39 do not lie on a straight line through the pin 37, but rather 30 lie on a line passing to the right of pin 37 as seen in Fig. 5. That is, it passes between the pins 37 and 40. Similarly the points of fastening of the same springs to the spreader 39 lie on a line which passes between the pin 40 and pin 37. This arrangement causes the springs 43 and 44 to tend 35 always to hold the spreaders 38 and 39 in positions substantially perpendicular to the line through the pivots 37 and 40. Consequently, when the lever 28 carries the pivot 37 down, the spreader 39 tends to rotate in a counterclock-wise direction as viewed in Fig. 5 about its pivot 43 but is prevented from doing so by its engagement with the latch piece 46. In this position, the spreader 39 is hooked over the latch piece 46 so as to prevent the arm 32 of the over-running 40 clutch from moving away from the position in which it is shown in Fig. 5.

This mechanism for handling and detecting the presence of the coin or similar piece and for locking the snap mechanism, operates as follows: 45 Assume that a coin has been inserted through the opening 86 so that it lies between the end of the slide 78 and the projection 83 on the slide 77 in the channel formed by the piece 75. When the hand lever 18 is depressed the arm 28 moves downward to tension the springs 43 and 44; and the arm 94, also, moves downward to move the slider 77 toward the right in Fig. 8. As the slider 77 moves toward the right in Fig. 8, its projection 60 83 moves the coin towards the right until the coin engages the end of the slider 78. Continued motion of the arm 18 moves the slider 78 towards the right (as seen in Fig. 8), so as to move the latch piece 46 towards the left as viewed in Fig. 3 65 so that it slips out of the notch of the spreader 39. This immediately releases the spreader 39 and permits it to assume a position perpendicular to the line through the pivots 37 and 40. Inasmuch as at the time this takes place, the 70 75

5 pivot 37 will be much lower than it is shown in Fig. 5, this causes the spreader 39 to rotate counterclock-wise as viewed in Fig. 5. At about this same time, or slightly later, the slide 77 moves 10 the coin over the opening into the coin trap 91 whereupon the coin is forced into the trap 91 by the slider 78 and its spring 85. This causes the latch piece 46 to move towards the right as viewed in Fig. 3 so that it stops against the side of the spreader 39. However, inasmuch as the spreader 15 already has rotated counterclock-wise from the normal position in which it is shown in Fig. 5, the latch piece 46 does not re-enter the notch of the spreader 39.

15 If now the handle 18 is released, the arm 28 will carry the pivot 37 back to the position of Fig. 5 but the spreader 39 will be unable to assume the position shown for it in Fig. 5 because it will be prevented from rotating to that position 20 by the projection 47 of the latch piece 46. In this condition of the apparatus, the coin rests on the pin 90 in the coin trap 91, and the operation of the snap mechanism which drives the wheel 30 is no longer blocked. In other words, 25 the operation of the handle 18 sufficient to bring the coin into the coin trap 91 has unlocked the snap mechanism. The release of the handle 18 at this point does not interfere with the correct operation of the machine. If the handle 18 30 now is carried to its extreme low position the snap mechanism will move the arm 32 from the position in which it is shown in Fig. 5 down to a position in which it rests against the boss 36. This sets the wheel 30 into motion in the manner 35 which already has been described, and it rotates the shaft 110 in a counterclockwise direction as viewed in Fig. 5 due to the engagement with the curved arm 111 of the roller carried by the arm 32. This motion of the shaft 110 withdraws the 40 pin 90 from the coin trap 91 so as to permit the coin to fall into the chute 101. The pin 90, as it is withdrawn, engages the extension 105 of the chute 101 and moves the same against the panel 72 so that the coin released by the pin 90 is 45 caught on the projections 103 and 104 and held in the opening 73 where it may be viewed by the player.

50 The rotation of the shaft 110, also, has brought the catch 120 (see Figs. 10 and 11) into engagement with the lever 80 so as to prevent the return of the slide 77 (see Fig. 8) towards the left.

This operation of the shaft 110, also, has lifted a catch 116 to operate the vending mechanism in a manner which will be described more in detail presently.

55 When the handle 18 (and with it the lever 28) is permitted to return towards normal position, it moves the lever 94 back toward the position in which it is shown in Fig. 3, but the lever 80 is held temporarily in its operated position by the latch 120. The return motion of the lever 94 towards its normal position brings the cam 95 into engagement with the projection 106 of the chute 101 to hold this chute closed to retain the coin in view in the opening 102. As the arm 28 approaches its normal position which is shown in Fig. 5, the arm 32 snaps back to the position shown in Fig. 5 and in so doing permits the arm 111 to return to its normal position, also, shown in Fig. 5 so as to release the catch 120 which is holding lever 80. This permits the slide 77 to return to its normal position. This action of the latch 120 and slide 77 serves to prevent a second coin from being inserted without again spinning 70 the wheel 30.

The spreader 39 just prior to the return of the arm 32 to its normal position is rotated slightly in a clock-wise direction from the position shown in Fig. 5 due to the action of the springs 43 and 44 already described. As the arm 32 returns to 5 its normal position it carries the spreader 39 with it and the spreader 39 rotates counterclock-wise as it rises with the arm 32. Consequently the left edge of the spreader 39 (the edge having the notch) is brought into engagement with 10 the end of the latch piece 46 and as the arm 32 comes to rest, the notch in the spreader 39 slips over the latch piece 46.

This leaves the apparatus again in its normal position with the coin in view behind the opening 102. If now the arm 18 is depressed with or without the insertion of an additional coin the initial motion of the lever 94 causes the cam 95 to release the chute 101 so that the coin may drop therefrom into a coin pan 122 located below it.

15 On the front of the panel 72 is an electric lamp 125 so located that it will illuminate both the coin on display in the opening 102 and the numbers on the periphery of the wheel 30 which are 20 in view through the opening 70. One terminal of this lamp is grounded to the metal of the panel 72. The other terminal carries a wire which runs to one terminal of the dry cell battery 126. A wire extends from the other terminal of the battery 126 to one terminal of a switch 127 which is adapted to be operated by a cam 128 carried by the shaft 27. The other terminal of the switch is grounded to the apparatus. The switch 127 is normally open so that the lamp is de-energized 30 when the apparatus is in the normal position in which it is shown in Figs. 3 and 5. The cam 128 is arranged to close the contacts 127 in response to the initial motion of the hand lever 18 from its normal position and to keep the contact 40 127 closed until the handle again returns to its normal position. The slot in the link 93 permits this initial motion to be made for turning on the light without operating the lever 94 to discharge the coin from its display position within 45 the opening 102. The circuit connections for the lamp are shown diagrammatically in Fig. 4.

The mechanism for delivering the confection or other article to the purchaser is illustrated 50 best in Figs. 6 and 7. A partition 131 serves to form a hopper for the storage of confection or the like in the left end of the apparatus as viewed in Fig. 1. Preferably the confection is in the form of balls to permit it to be handled easily 55 by simple equipment. Located below the hopper is a casting 132 which has a passage opening into the bottom of the hopper near the rear portion thereof and which is of such size as to conduct balls from the hopper in single file as shown in 60 the sectional view of Fig. 7. The balls within the passage of the casting 132, rest upon a plate 133 which slides on pins or rivets 134. A spring 135 holds this plate normally forward. In the position in which it is shown in the drawings, the 65 plate 133 is in its extreme forward position so as to bring an extruded hole 137 therein in register with the curved forward end of the passageway in the casting 132 (see Fig. 7). In this position, a ball may enter the opening 137 and rest 70 on a projection or stop 138 with its top surface approximately level with the top surface of the plate 133. With the apparatus in this condition, the purchaser may press the plunger 19 which moves the plate 133 back so that the ball 75 139

5 drops off the projection 138 and is delivered in the delivery spout 29. As the plate 133 is pushed back, the catch 116 already described falls into position to engage a projection 142 of the plate 133 so as to retain the plate in that position. In this position, the opening 137 in the plate 133 is out of register with the passage-way within the casting 132 so that another ball may not enter the same.

10 A subsequent operation of the apparatus including the insertion of a coin and the operation of the lever 18 to again actuate the shaft 110, will again cause the catch 116 to rise so as to release the plate 133 and allow it to move 15 under the action of the spring 135 to its forward position where another ball will fall into the opening 137 ready to be delivered when the plunger 19 is pressed.

20 The arm 145 of the shaft 110 does not directly lift the catch 116 since if it did so it would prevent the catch 116 from holding the plate 133 if the plunger should be pressed with the handle 18 held in its depressed position. The arm 145 loosely carries a weight 146 which is of such dimension that the arm may not drive the catch 116 therethrough. The weight 146 is adapted to be thrown up by the arm 145 so that it strikes against the catch 116 causing the catch 116 to rise and disengage the projection 142 of the 25 plate 133. The plate 133 immediately snaps to the right (See Fig. 6) under force of the spring 135 and the catch 116 drops and rests on the projection 142 as shown, ready again to latch the plate 133 when it is forced back by the plunger 19.

30 In order to prevent the machine from receiving coins after the supply of confections is exhausted from the hopper, a wire feeler 151 extends through the partition 131 into the passage-way 40 in the casting 132, and extends over the opening in the plate 133. A cam 150 riveted to the plate 133 is adapted to lift the wire feeler 151 up to the top of the passage-way when the plate 133 is in its forward position as shown in Fig. 6 45 so as not to obstruct the movement of the balls. When the plunger 19 is pressed in to move the plate 133 back so as to deliver one of the balls, the cam 150 leaves the wire feeler 151 and permits it to fall. If any balls remain in the passage-way in the casting 132 the wire 151 rests on them, but if no balls are in the passage-way the wire 151 drops until it rests on the cam 150. The wire 151 when in this position, lies 50 lower in the passage-way than it does when resting on the balls. The wire 151 is carried on a pivot 155 having a horizontal axis and mounted on the partition 131. The wire 151 has rigidly attached thereto an arm 152 which extends back and upward and carries at its upper end a sheet metal flag 153, which is pivoted thereto. This metal flag 153 is adapted to cover and uncover the coin aperture 15 in the sleeve 13 of the enclosing case (see Fig. 1), and, also, the coin aperture 86 in the panel 72.

55 This mechanism operates as follows. Assume that the apparatus contains only two balls of confection and that the plate 133 is in the position in which it is shown in Fig. 6. One of the two balls will lie in the extruded hole 137 in the plate 133 being supported on the projection 138, and the other ball will rest either on top of the first one or on the surface of plate 133. Pressing the plunger 19 moves the plate 133 back 60 to deliver the first ball into the pocket 29, and

engages the catch 116 which retains the plate 133 in its back position.

65 The cam 150 will have released the wire feeler 151, but the wire 151 will rest on the one remaining ball, which, in turn, rests on the surface of plate 133. Therefore, the flag 153 will leave the coin opening unobstructed.

70 The insertion of a coin and the operation of the machine by means of handle 18 releases the catch 116 so that the plate 133 again moves forward and permits the one remaining ball to drop into the extruded opening in the plate 133 where it rests on the projection 138. The plunger 19 again may be pressed to deliver the last ball into the pocket 29. When the cam 150 releases the wire 151, as the plate moves back and engages the catch 116, the wire 151 drops to a low position in the passage in the casting 132 and moves the flag 153 over the coin openings 86 and 15 so as to prevent any further coins from being inserted 20 into the machine.

75 The operation of the complete apparatus is as follows: Assuming that the confection hopper contains a supply of the confection in the form of balls or the like, so that the coin openings are 25 unobstructed, a coin may be inserted into the machine by pressing it into the hollow of the casting 14 from which it drops through the slots 15 and 86 into the space between the end of the slide 78 and the projection 93 carried by the 30 slide 77. The hand lever 18 may be depressed to operate the machine. The initial motion thereof operates the switch 127, turns on the light 125 to illuminate the interior of the machine to aid the view had thereof by the player. As the lever 35 18 moves downward, the link 93 takes up the slack provided by its slot and then actuates the lever 94.

80 The cam 95 of the lever 94 moves away from the arm 106 of the chute 101 so as to open the 40 same and permit any coin therein to drop into the coin box 122. Continued motion of the hand lever 18 drives the slide 77 to the right (Figs. 8 and 9), and because of the presence of the coin, also, drives the slide 78 toward the right to disengage the latch piece 46 from the slot 45 in the spreader 39 of the snap mechanism. Subsequently, or at about the same time, the coin comes into register with the opening between the channel containing the slides 77 and 78 and 50 the coin trap 91 so that it is ejected into the trap 91 where it rests on the pin 90. During the entire motion of the hand lever 18 the springs 43 and 44 have been lengthening and the line of action of the springs (the line through the center 55 of the pins 37 and 40) has been approaching the axis of shaft 31. Subsequent to the discharge of the coin into the trap 91 the arm 32 of the snap mechanism snaps down to its lower position where it stops against the boss 36, and in so 60 doing sets the wheel 30 into motion in the manner already described.

65 The arm 32 in moving to its lower position, also, has moved the arm 111 to the right as seen in Fig. 3 so as to perform the following operations: (1) The catch 120 has been brought into position to block the lever 88 so as to prevent the return of the slide 77 to its normal position in which it could receive another coin; (2) the arm 88 has withdrawn the pin 90 from the coin trap 70 91, and in so doing has engaged the arm 105 of the chute 101 to close the chute by moving it against the panel 72. This has permitted the coin to drop into position where it may be viewed easily in the opening 102; (3) the arm 145 has 75

thrown the weight 146 against the catch 116 to lift the same so as to release the plate 133 to permit it to move into its forward position so that the plunger 19 again may be pressed to deliver 5 one of the balls into the pocket 20.

The wheel 30 which has been set into motion by the snap mechanism spins freely and eventually comes to a random stop with the dog 67 carried by the weight 60 seated in one of the notches 10 68 and the notched wheel 69. This brings one of the characters of the design on the periphery of the wheel 30 squarely registered in the opening 70 to indicate the random selection of the machine. This takes place automatically regardless of whether or not the player permits the lever 18 to return to its normal position, and the stopping of the wheel 30 may take place either before or after the hand lever 18 is permitted to return. As the player permits the hand lever 18 15 to rise, the lever 94 moves under force of its spring back to its normal position so that the cam 95 engages the arm 106 of the chute 101 to hold it in its closed position. The catch 120 continues to hold the lever 80 and the slide 17 20 in their extreme right position as viewed in Figs. 8 and 9. When the lever 18 has substantially completed its return motion, the line of action of the springs between the pins 37 and 40 again crosses the axis of the shaft 31 so that the arm 32 25 snaps back to its normal or upper position where it stops against the boss 35. In so doing it permits the arm 111 to return to its normal position. This rotates the shaft 110 to accomplish the following: (1) The catch 120 releases the arm 80 so that the slide 17 snaps back under 30 the force of its spring 81 to its normal position in which it is shown in Fig. 8; (2) the arm 89 moves the pin 90 into the coin trap 91. While the arm 89 moves away from the arm of the chute 101, the chute does not open because it is held 35 by the cam 95 of the arm 94. The action of the arm 32 in snapping to its normal or upper position does not rotate the wheel 30 because the over-running clutch does not permit the arm 32 40 to drive the wheel in a counter-clockwise direction as viewed in Fig. 5. The final motion of the hand lever 18 to its normal position causes the cam 128 to ride off the switch 126 so as to open the circuit to the lamp 125.

50 The hand lever 18 now may be depressed slightly to turn on the light 125 to provide a good view of the coin and of the exposed and registered character on the periphery of the wheel 30. The hand lever 18, also, may be depressed a considerable portion of its stroke so as to actuate the lever 94 so that the cam 95 releases the arm 106 55 to open the chute 101 and drop the coin from its position behind the opening 102 in the panel 72 into the coin box 122. This operation of the hand lever 18 does not cause the wheel to spin because since no coin has been inserted into the space between the end of the slide 78 and the projection 83 on the slide 77, the latch piece 46 will continue to engage the notch 45 in the spreader 39 60 so as to prevent the operation of the arm 32 in the manner already described.

While I have shown and described a single specific embodiment of my present invention, it 70 will be apparent to those skilled in the art that the same is by way of illustration only, and that the invention is capable of numerous modifications and variations. Therefore, I do not wish to be limited except by the scope of the appended 75 claims.

I claim:

1. In combination in an apparatus of the class described, an enclosing case having an aperture therein adapted to receive a coin, said case including means for permitting a view of the interior of said case, a handle on the exterior of the case, coin controlled means within said case adapted to receive said coin from said aperture, a wheel within said case, means operated by said handle under control of said coin controlled 5 means for spinning said wheel, means for providing a plurality of registered positions of said wheel and for stopping said wheel in one of said positions at random, an index, said wheel having a display comprising a plurality of characters 10 thereon each one of which characters registers with said index at some registered position of said wheel, said index and the character in register therewith being exposed to view from the exterior of said case, means including said coin controlled 15 means operated by said handle when said wheel is spun for moving said coin into an exposed position near said index and the character registered therewith so that said character and coin 20 may be viewed together, means operated by said handle independently of any control by said coin controlled means and irrespective of the operation of said wheel for removing said coin from view, means comprising an electric light for illuminating said coin in said exposed position and for illuminating the character which is in register with said index, a battery for said light, and a switch operated by said handle for connecting said light to said battery and disconnecting it 25 30 35 therefrom.

2. In combination in a device of the class described, an enclosing case having an aperture adapted to receive a coin or the like, said case including means permitting a view of the interior thereof, said case including a compartment for the storage and accumulation of coins and the like, a handle on the exterior of said case, coin controlled means within said case adapted to receive a coin from said aperture, apparatus within said case adapted to be operated by said handle under control of said coin controlled means, means adapted to receive a coin from said coin controlled means when said apparatus is actuated by said lever and thereupon to expose said coin to view from the exterior of said case, means operated by said handle independently of any control of said coin controlled means for removing said coin from view and depositing it in said compartment. 40 45 50 55

3. In combination in a device of the class described, an enclosing case having an aperture adapted to receive a coin or the like, said case including means permitting a view of the interior thereof, said case also including a compartment for the storage and accumulation of coins and the like, a handle on the exterior of said case, coin controlled means within said case adapted to receive a coin from said aperture, apparatus within said case adapted to be operated by said handle under control of said coin controlled means, means adapted to receive a coin from said coin controlled means when said apparatus is actuated by said lever and thereupon to expose said coin to view from the exterior of said case, 60 65 70 means operated by said handle independently of any control by said coin controlled means for removing said coin from view and depositing it in said compartment, a lens for magnifying the view of a coin exposed to view as aforesaid, an electric 75

lamp for illuminating a coin exposed to view as aforesaid, a battery for operating said lamp, and a switch operated by said handle to turn on said lamp when said apparatus is actuated and when 5 said coin is removed from view.

4. In combination in an apparatus of the class described, an enclosing case having an aperture adapted to receive coins or the like, said case including first means for permitting a view of the 10 interior thereof, a handle on the exterior of said case, apparatus within said case adapted to be operated by said handle, second means adapted to receive coins from said aperture and operable by 15 said handle to expose said coins to view from the exterior of said case and then to remove them from view, said handle being operable to operate said apparatus each time a new coin is exposed to view and actuate said second means for removing a coin from view each time said apparatus is 20 operated, said handle being at all times operable to remove a coin from view regardless of whether or not a new coin is exposed to view thereby.

5. A device as defined in the immediately preceding claim wherein said second means includes 25 coin controlled means for compelling a new coin

to be exposed to view each time said apparatus is operated.

6. In combination in a device of the class described, an enclosing case having an aperture adapted to receive coins or the like, said case including first means permitting a view of the interior thereof, a handle on the exterior of said case, apparatus within said case adapted to be operated by said handle, second means adapted to receive coins from said aperture and including 10 coin controlled means operated by said handle to display coins, said second means including also third means for removing said coins from view, said handle being operable to operate said apparatus each time a new coin is exposed to view 15 and to actuate said third means each time said apparatus is operated, an electric lamp adapted to illuminate a coin while on display and means controlled by said handle for energizing said lamp each time said handle is actuated regardless of 20 whether or not a new coin is exposed to view thereby, said last named means being operable normally to deenergize said lamp.

ARCHIE J. McMASTER. 25
